[57] CLAIM

The ornamental design for door hardware, as shown and described.

DESCRIPTION

FIG. 1 is a perspective view of door hardware showing my new design;

FIG. 2 is a front elevational view thereof;

FIG. 3 is a top plan view thereof;

FIG. 4 is a right side elevational view thereof;

FIG. 5 is a rear elevational view thereof;

FIG. 6 is a left side elevational view thereof;

FIG. 7 is a top plan view of a second embodiment of the design of FIG. 1, the only difference being the mirror image configuration of the right pull.

FIG. 1

FIG. 2

FIG. 3

FIG. 4

FIG. 5

FIG. 6

FIG. 7

FIG. 8
